DRYING APPARATUS

Gustav Schwietert, McGregor, Iowa

Application December 7, 1946, Serial No. 714,800

3 Claims. (Cl. 263—32)

1

This invention relates to drying apparatus and to a method of drying. The invention is particularly useful in the drying of grain, hay, and other materials from which moisture should be removed.

An object of the invention is to provide apparatus and method steps enabling grain, hay, and other materials to be effectively dried at relatively low temperatures and while producing a final product of unusually high quality. A further object is to provide means and method steps whereby the direct rays of a heating medium, including infra-red and ultra-violet rays, are caused to impinge directly upon the product being dried and in which a rotating heated body of air is caused to traverse the zone in which the materials are being dried. Yet another object is to provide a heating zone in which material to be dried is rotated while being maintained under partial vacuum and at relatively low temperatures. Yet another object is to provide mechanism in which material to be dried is rotated in contact with heated air and under a partial vacuum and then passed through a suction zone and into a pressure-separating zone from which the material is drawn with a cooling current of air into a second collecting zone. Yet another object is to provide effective means for distributing the material being dried uniformly throughout a heating zone so as to effectively contact the material with the incoming heated air. Other specific objects and advantages will appear as the specification proceeds.

The invention is illustrated, in a preferred embodiment, by the accompanying drawing, in which—

Figure 1 is a broken longitudinal sectional view of apparatus embodying my invention; and Fig. 2, a broken transverse sectional view, the section being taken as indicated at line 2—2 of Fig. 1.

In the illustration given, 10 designates a drying cylinder which may be circular in cross section or of any other desired contour. The cylinder is provided with reinforcing rings 11 and toward its ends with bearing rings 12. The bearing rings 12 rest upon anti-friction rollers 13 supported in trunnions 14. The shaft of one of the rollers 13 is extended and is provided with a gear 15 meshing with a drive gear 16. The drive gear 16 is mounted upon the shaft 17 and at the other end of the shaft 17 is mounted a gear 18. It will be understood that the shaft 17 is driven by any suitable power means. The trunnions 14 of rollers 13 are supported upon the base 19.

2

At the lefthand side of the cylinder 10 is a heater casing 20 which provides air inlet passages 21 and a combustion chamber 22. A fuel pipe 23 for oil or any suitable heating fluid passes into the chamber 22 and is discharged through a nozzle 24. Curved vanes 25 direct the incoming preheated air about the nozzle 24 so as to cause the air to rotate within the chamber 22. Fire brick 26 is supported about the nozzle 24 and, if desired, may be extended about the entire or most of the chamber 22. The stationary casing 20 preferably carries a ring flange member 27 which extends over and forms a relatively tight joint with the rotatable casing 10.

The stationary casing 20 is also provided with a chute 28 entering through the top or side wall of the casing 20 and discharging through the outlet 29 into the interior of cylinder 10. It will be understood that any suitable means, such as, for example, an endless chain conveyor, may be employed for carrying grain or other material upwardly and discharging the same into the open end of the chute 28; or, if desired, the material may be introduced by hand or by any other means into the chute.

The cylinder 10 is provided on its inner side with a plurality of fins 30 extending in parallel and longitudinally of the cylinder. I also prefer to provide fins 31 spaced about the cylinder and provided with forwardly-extending distributor ledges 32. The ledges 32 serve to hold a portion of the grain, alfalfa, or other material upon the fin and to release it gradually as the cylinder rotates, thus producing a relatively uniform distribution of the material to be dried across the interior of the cylinder.

Near the exit end of the cylinder 10, I provide a fixed baffle 33 which extends between the fins 30 and 31 and completely closes off the central portion of the cylinder 10, thus causing the material to be brought to pass around the baffle 33 and along the fins 30 and 31.

The cylinder 10 is provided at its exit end with a closure plate 34 having an outlet aperture 35. In front of the aperture 35 I provide a baffle plate 36 fixed to and upon a rotatably-mounted baffle gear 37 so that the baffle may be moved to various positions by the dotted lines 38. The position of the gear 37 is controlled by the bevel gear 39 mounted upon control shaft 40. The shaft 40 is rotatably mounted within the sleeve 41 mounted upon bracket 42. The shaft 40 is provided with a removable control handle.

Communicating with the outlet 35 of cylinder 10 is a fan casing 43 providing a fan chamber 44.

A shaft 45 extends into the chamber 44 and supports the fan 46. From the fan casing 43 extends a duct 47 and the duct leads to a separator cone or chamber 48. The chamber 48 may be provided of any suitable type of casing and may be of any suitable shape. I prefer to employ a casing providing a top chamber having a frusto-conical bottom portion 49 leading to an outlet 50. Preferably, the chamber is provided at its top with an upwardly-extending portion 51 having a vapor outlet at its top. If desired, the vapor outlet may be provided with a cone cap or any other suitable type of cap. The outlet portion 50 of the chamber 48 communicates with a duct 52 provided with a valve-controlled fresh air inlet 53. The duct leads to a fan chamber 54, and the fan within chamber 54 and carried by shaft 45 discharges the material and the cool air through a duct 55 to any desired point of destination. For example, the cooled material may be discharged into a second conical separator similar to chamber 48 and provided with a vapor outlet, the grain or other dried material being discharged through the lower portion of the separator into a hammer mill or in any desired receptacle. It is sufficient to show the passing of the material with its cool charge of air through duct 55 which may lead to any desired destination for further treatment or storage.

The shaft 45 controlling the two fans may be driven by any suitable power source. In the illustration given, a drive chain 56 connects the sprocket gear 18 and the gear 57 on shaft 45.

Operation

In the operation of the device, grain, alfalfa, or any other desired material to be dried, is introduced through the chute 28 into the interior of cylinder 10. Gaseous or liquid fuel is introduced through line 23 and atomizer head 24 and ignited within the combustion chamber 22. Air passes through the inlets 21 about the combustion chamber 22 where it is preheated and finally is discharged by the vanes 25 in a rotating annulus about the combustion chamber. The air thus heated is directed toward the interior of casing 10. Since there is no partition wall between the open combustion chamber 22 and the interior of casing 10, the air flows forwardly in its rotational form into the cylinder, while at the same time the rays of the burning gases, including the infra-red and ultra-violet rays, impinge directly upon the products being dried.

The cylinder 10 is maintained in rotation by the drive shaft 17 through gears 16 and 15 and the fins 30 and 31 constantly lift the material as it passes through the cylinder and discharge it within the interior of the cylinder. The fins 31, with their distribution ledges 32, effectively carry and gradually release the material to be dried as the cylinder rotates. It will be understood that the ledges 32 may be made shorter or longer in order to adapt them to any particular type of material being dried.

An effective partial vacuum is maintained within the chamber of casing 10 by means of the fan 46 carried by shaft 45, and the suction thus provided assists in the drying of the product to be dried through the material and into the fan chamber 44. I find that the effect of suction is increased by employing a stationary baffle 33 extending between the fins 30 and 31, and further that the drying effect is enhanced by causing the material to pass along the fins 30 and 31. I find further that the suction effect should be varied

depending upon the type of material employed and that such variance can be effectively controlled through the rotatable baffle 36 controlled by shaft 40. By moving the baffle to a position in parallel with the member 40, there is a minimum of resistance to air flow, while the resistance is increased as the baffle is moved toward the transverse position illustrated in Fig. 1.

After the material has passed through the cylinder 10 and is discharged into the fan chamber 44 under the influence of suction, the fan 46 then moves the material outwardly under pressure through duct 47 to the separating chamber 48. Here, the vapors are free to discharge through the upwardly-extending outlet 51 while the grain or other material drops downwardly toward the solids outlet 50. At the point of discharge 50, fresh and cool air is drawn through the opening 53 and, under the influence of the fan in chamber 54, the solids are drawn with the cooling medium through duct 52 and thence through chamber 54. The material is then discharged through duct 55 into any further separating or treating structures or to any desired destination.

It will be noted that the above relatively simple and compact apparatus results in the removal of moisture from the material and while the same is maintained under partial vacuum, while permitting under a pressure zone the removal of vapors and the cooling of the solids through the intake of fresh air.

I have found that beneficial effects upon the drying material, such as grain, hay, etc., are produced through the exposure thereof to the direct rays of the flame in the combustion chamber, and further that more effective drying is produced by taking the heated and rotating gases in the combustion chamber directly into the rotating cylinder 10.

I have found that by maintaining the cylinder 10 under partial vacuum that effective drying is produced at relatively low temperatures which do not scorch or in any way damage the product. By maintaining the pressure below atmospheric, the drying operation can be effectively carried out with large volume while maintaining the temperature slightly below the boiling point of water or in the neighborhood of this temperature. Fairly satisfactory drying has been produced when the temperature at the inlet and of the drying chamber is maintained in the range of 210°-215° F. It will be noted that the single fan 46 is effective as a suction-producing instrument for controlling the interior of cylinder 10 while at the same time it is effective as a pressure means for discharging the material through duct 47 into the separating chamber 48. Here, vapors are liberated and the dried grain or other solids drop downwardly to an outlet point where they are picked up by a volume of fresh air. The fresh air serves as a means for conveying the grain or other solids and also as a means for cooling the same as it is discharged toward the next treating operation or destination point.

In the forming of the fire clay bed 26, I prefer to employ a high content of aluminum oxide in the fire clay so as to eliminate case hardening, etc.

The baffle 36 serves the important function of preventing the withdrawal of heavy and moist material before it is fully dried. For example, a material too moist and heavy to float in air by suction will strike this plate and be drawn back toward the source of heat, resulting in more uniform drying. Reversing the baffle 36, as in

dicated in dotted lines in the drawing, enables heavy weight grains, such as corn and beans, too heavy to be lifted by air, into the exhaust fan.

The drying apparatus is useful not only in the drying of grain, alfalfa, and other types of crops, but also in the drying of many other objects and materials not herein listed.

While in the foregoing specification, I have set forth in considerable detail specific apparatus and process steps as illustrative of the invention, it will be understood that such details may be varied widely by those skilled in the art without departing from the spirit of my invention.

I claim:

1. In drying apparatus, a stationary casing providing a combustion chamber, means for introducing fuel into said combustion chamber for burning, vanes supported about said fuel line, means for introducing air against said vanes to produce a rotating body of gas within said combustion chamber, a frame, a cylindrical casing communicating at one end with said combustion chamber and supported in said frame for rotation, a fixed end plate closing the other end of said cylinder and equipped centrally with an outlet opening, fins within said casing extending longitudinally thereof, an inlet chute for directing material to be dried directly into the open end of said cylindrical casing, baffles extending centrally across said cylindrical casing but spaced from the inner walls of said casing, means for rotating said casing, a conduit communicating with the outlet opening of said end plate, and means for producing subatmospheric pressure within said conduit.

2. In drying apparatus, a frame, a cylindrical casing mounted in said frame for rotation, a stationary casing, closed at one end and communicating at its other end with the open end of said first-mentioned casing, means for injecting fuel into said stationary casing, means for supplying air to said stationary casing, deflector vanes for rotating said incoming air, fins extending longitudinally of said cylindrical casing for arresting rotary movement of said air, means for introducing material to be dried into the open end portion of said rotating casing, an end plate closing the end of the casing opposite said stationary casing, said end plate being equipped with

an outlet opening, and a fan-equipped exhaust conduit communicating with said end plate opening.

3. In drying apparatus, a frame, a cylindrical casing mounted in said frame for rotation, a stationary casing closed at one end and communicating at its other end with the open end of said first-mentioned casing, means for injecting fuel and air into said stationary casing, deflector vanes for rotating said air, means for arresting the rotation of said air within said cylindrical casing and comprising longitudinally-extending fins extending inwardly from the cylindrical casing and terminating to provide a free central passage, a baffle extending centrally across the cylindrical casing near the end thereof opposite said stationary casing but spaced inwardly from the inner walls of said casing, an end plate closing the end of the casing opposite said fixed casing and provided with a central discharge opening, a fan-equipped exhaust conduit communicating with said end plate opening, and means for introducing material to be dried into the end of said cylindrical casing adjacent said stationary casing.

25 GUSTAV SCHWIETERT.
